R. L. BASICH

ROAD GAUGE

Filed Jan. 18, 1927

INVENTOR.

Risto Ir. Basich
BY

Robt. G. Pearson
ATTORNEY.

UNITED STATES PATENT OFFICE.

RISTO L. BASICH, OF LOS ANGELES, CALIFORNIA.

ROAD GAUGE.

Application filed January 18, 1927. Serial No. 161,845.

This invention relates to road gauges especially adapted to be used in the construction of roadways and streets for the purpose of facilitating the proper grading and leveling of the cementitious material used in its construction as well as providing temporary supports for re-inforcing rods or wires, incorporated in the road in a desired position while the material is being poured.

10 The invention also contemplates provision of means whereby the supports and the whole structure may be disconnected and removed, before the material has become set, without disturbing the position of the reinforcing rods.

The above and other objects of the invention will be more fully disclosed in the following specification and exemplified in the accompanying drawings, in which:

20 Figure 1 is a transverse section through somewhat over a half of a roadbed showing the invention set up in proper position for the pouring of the cement.

Figure 2 is a fragmental plan view of the same.

Figure 3 is an enlarged detail partly in section, illustrating certain features of the construction of the gauge.

In carrying out the invention, 5 represents the dirt surface of the road as prepared for the reception of the cement and other surfacing material and arranged at the sides thereof are the side form rails 6, only one of which is shown, and the central form rail 7, 30 all of which are longitudinally disposed along the road bed.

A plurality of bars 8, preferably formed of strap metal, are suitably spaced apart and disposed transversely of the road the 40 ends of said bars resting on and preferably hooked to the side rails 6, and also resting on the central rail 7 and secured thereto against lateral displacement. These bars 8 may be formed all in one piece or formed 45 of sections 9, 10, etcetera, and are provided with a plurality of vertically disposed apertures 11 for the reception of the gauge bolts 12 the lower ends of which are adapted to rest upon the dirt surface of the roadway as 50 clearly shown in Figure 1 of the drawings.

The bolts 12 are suitably threaded and the bars 8 or its sections are adjustably supported thereon by means of the double lock nuts 13 and 14, which are threaded on the 55 bolts and disposed adjacent the top and bot-

tom surfaces of said bar to allow the bolts 12 to turn in said sections 9—10. Thus the bars 8 may be adjusted with reference to the dirt surface and to form gauges to determine the surface of the cement material 60 when poured.

Each of the bolts 12 is provided with a suitable handle 15, for revolving the same, at its top end, and throughout its length with a plurality of transversely disposed apertures 16 for the reception of the transversely disposed pins 17. By this arrangement, one or more pins 17 which constitute supports for a reinforcing material may be secured to each bolt, and said pins may be 70 placed into any desired apertures so as to adjust them with respect to the dirt surface.

When the structure is set up for use, the pins 17 on bolts 12 are disposed transversely of the road bed and disposed longitudinally 75 and resting on said pins are placed the reinforcing rods or wire 18 and supported on these rods or wires are the transversely disposed rods or wires 19.

The ends of bars 8 are provided with 80 downwardly projecting lugs 20 adapted to rest on opposite sides of rails 6, thus holding said bars firmly in adjusted position.

A bolt 21 passes through one of the perforations 11 of bar 8 and is adjustably secured thereto in a similar manner to that of bolts 12 and is provided at its lower end with a fork 22 adapted to engage with the centrally disposed rail 7, in order that the bars 8 may be more firmly and accurately 90 supported at their centers.

The bars 8 may be provided with suitable handles 23 to facilitate the transportation and adjustment of the same.

When the gauge is made up in sections, 95 section 9 is supported by the gripping of the lugs 20 to the plate 6 and also by the lower ends of bolts 12 which rest upon the ground and if desired may be embedded therein. Section 10 is supported by the 100 fork 22 and also by the bolts 12 which rest upon the ground and may be embedded therein.

The surfacing material may be poured up to a level with the bar 8 and graded in accordance therewith, and after it has partially set the bolts 12 may be given a quarter turn, thus disengaging the pins 17 from the rods or wires 18, and then the entire structure may be readily bodily withdrawn from 110

the material by use of the handles 23, without disturbing the reinforcing rods, and then the damaged places retroealed.

Having thus described my invention what I claim is:

1. A road gauge comprising a bar and a bolt mounted in said bar adapted for adjustment transversely in said bar, and means on said bolt for supporting a reinforcing material.

2. A road gauge comprising a bar and a bolt mounted for rotation in said bar adapted for adjustment transversely in said bar, and a pin secured to said bolt and projecting laterally therefrom.

3. A road gauge comprising a bar and a bolt mounted for rotation in said bar adapted for adjustment transversely in said bar, a reinforcing material support and means whereby said support may be mounted on said bolt at different heights.

4. A road gauge comprising a supporting bar, bolts turnably mounted in said bar and means for detachably holding reinforcing material on said bolts.

5. A road gauge comprising a bar, a reinforcing material support, and means for detachably mounting said support on said bar at different heights and means whereby the support may be withdrawn from supporting position.

6. A road gauge comprising a bar, and a bolt mounted in said bar adapted for adjustment transversely therein, said bolt being provided with a plurality of apertures spaced longitudinally thereof, and pins adapted to fit in any of said apertures for supporting reinforcing material.

In testimony whereof I affix my signature.

RISTO L. BASICH.
